MIMEOGRAPHER

Benjamin Gold, New York, N. Y.

Application November 12, 1942, Serial No. 465,367

6 Claims. (Cl. 101—125)

This invention relates to new and useful improvements in a Mimeograph of post card, note or letter size.

More specifically, the invention proposes the construction of a postal card size Mimeograph characterized by a top plate which is extended across the flat top face of a platen having a curved bottom face for a pad and stencil with the ends of the stencil being directed inwards between the adjacent faces of the plate and platen in a manner to be securely clamped in position.

Another object of this invention is the provision of a screw means for urging the top plate into facial engagement with the top face of the platen in a manner to insure the clamping of the ends of the stencil as hereinabove mentioned.

Still further it is proposed to provide the bottom face of the top plate with downwardly extending transverse ribs for urging the ends of the stencil into complementary grooves formed in the end portions of the top face of the platen in a manner to take up the slack in the stencil when the ends are being clamped in position between the top plate and platen.

A further object of the invention proposes serrated bars upon which the ends of the stencil are adapted to be mounted and the provision of means for holding the bars in several longitudinal positions on the platen while the top slack in the stencil to be partially taken up before the top plate is securely clamped in position.

It is a further object of this invention to construct a postal card size Mimeograph which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a perspective view of a postal card size Mimeograph constructed in accordance with this invention.

Fig. 2 is a longitudinal vertical sectional view of Fig. 1, on an enlarged scale.

Fig. 3 is a plan view of the platen per se.

Fig. 4 is a bottom perspective view of the top plate per se.

Fig. 5 is a side elevational view of a postal card size Mimeograph constructed in accordance with a modification of this invention.

Fig. 6 is a reduced plan view of Fig. 5.

Fig. 7 is a partial longitudinal vertical sectional view on the line 7—7 of Fig. 6.

Fig. 8 is a side elevational view similar to a portion of Fig. 5 but illustrating the parts in a different position.

Fig. 9 is an enlarged partial longitudinal vertical sectional view on the line 9—9 of Fig. 6.

Fig. 10 is a plan view of the platen per se.

Fig. 11 is an enlarged perspective view of one end of one of the serrated bars per se.

Fig. 12 is a perspective view of the Mimeographer illustrated in use.

The postal card size Mimeographer, according to this invention, includes a platen 10 having a curved bottom face 11 and a flat top 12. A pad 13 and stencil 14 are extended across the curved bottom face 11 of the platen 10. The pad 13 is made up of a felt layer 15 which is securely adhesively attached to the curved bottom face of the platen 10 only, and a flannel layer 16 for ink disposed between the adjacent faces of the felt layer 15 and the stencil 14. The ends of the flannel layer 16 and the stencil 14 are adapted to be extended across the top face of the ends of the flat top 12 of the platen to be clamped in position thereon.

The stencil 14 is made of materials in common use for this purpose and is adapted to be cut on a typewriter or by hand by means of a stencil pen. When the stencil is engaged in position upon the Mimeographer pressure upon it will force ink through the indicia cut in the stencil to be imparted to the surface over which the platen 10 is rocked.

A top plate 17 extends across the top face of the platen 10 and has end portions for engaging against the ends of the stencil 14 and the flannel portion 16 of the pad 13. The top plate 17 is of a size substantially equal to the size of flat top 12 of the platen 10.

Screw means is provided for clamping the top plate 17 down on the flat top 12 of the platen 10. The interior of the platen 10 is hollow and formed with a central upwardly extending boss 18. A plurality of webs 19 extend radially from the boss 18 for reinforcing the side walls of the platen 10. A screw 20 has its bottom end fixedly imbedded in the boss 18 and a free top end projected through a central opening formed in the top plate 17 and beyond the top face thereof. A knob 22 is engageable upon the top end of the screw 20. The interior of the knob 22 carries a fixedly mounted internally threaded bushing 23 which is adapted to thread-

edly engage the top end of the screw 20. The knob 22 is adapted to be manually turned to bear against the top face of the top plate 17 and urge the top plate into facial contact with the flat top 12 of the platen 10.

The end portions of the bottom face of the top plate is formed with downwardly extending transverse ribs 24. These ribs 24 are arranged to force the ends of the stencil 14 and the flannel layer 16 into complementary grooves 25 formed in the end portions of the flat top 12 of the platen 10. These ribs 24 will force the stencil 14 and layer 16 into the grooves 25 while the top plate 17 is in the process of being clamped down upon the flat top 15 of the platen 10 to take up the slack in these portions and cause the stencil 14 and layer 16 to be tautly stretched across the curved bottom face of the platen 10.

The operation of this form of the invention is as follows:

The stencil 14 is first cut on a typewriter or by hand and then the flannel layer 16 is saturated with ink. The flannel layer is then superimposed upon the back face of the stencil and these layers are then extended across the curved bottom face of the platen 10 with the free face of the layer 16 engaging the face of the felt layer 15. The ends of the stencil 14 and layer 16 are then extended across the end portions of the top face of the platen 10 and over the grooves 25. The top plate 17 is then engaged upon the platen 10 with the free end of the screw 20 projecting upwards through the opening 21. The knob 22 is then manually turned onto the free end of the screw 20 clamping the top plate 17 in position upon the flat top 12 of the platen 10 causing the ribs 24 to force the ends of the stencil 14 and the layer 16 into the grooves 25 to tightly stretch the stencil and layer 16 across the curved face 11 of the platen 10. The Mimeograph is now completely assembled and ready to be used for imprinting the material cut in the stencil upon a desired surface by rocking the platen 10 thereover. To remove the stencil 14 the above procedure is reversed.

In Figs. 5 to 11 a modified form of Mimeograph is illustrated in which provision is made of initially taking up the slack in the stencil 14 and layer 16 before the top plate 17 is securely clamped down upon the flat top 12 of the platen 10. The means is characterized by spaced bars 30 which extend laterally of the platen 10 and are arranged to be moved manually towards each other. The inner edges of the bars 30 are formed with inwardly directed teeth 31 which are adapted to be engaged through the ends of the stencil 14 and the layer 16 to securely connect the ends of these parts with the bars 30. The bottom face of the ends of the bars 30 are formed with serrations 31 which engage complementary serrations 32 formed on the top edges of the side walls of the platen 10. Leaf springs 33 have one of their ends securely attached to the bottom face of the top plate 17 by means of pins 34. The free ends of the leaf springs 33 are arranged to bear against the top face of the ends of the bars 30. In the partially clamped down position of the top plate 17 the leaf springs 33 act to urge the bars 30 downwards causing the serrations 31 of the bars 30 to maintain their engaged position with the serrations 32 of the platen 10. This position is clearly illustrated in Fig. 8.

The ends of the bars 30 are projected beyond the sides of the platen 10 and plate 16 to be manually gripped and be moved inwards. With

the plate 17 in the position shown in Fig. 8 the serrations 31 of the bars 30 will ride over the serrations 32 of the platen 10 and the springs 33 will keep these teeth continually engaged. Movement of the bars 30 will cause the slack in the stencil 14 and layer 16 to be taken up before the top plate 17 is securely clamped down.

When the top plate 17 is completely clamped down by turning the knob 22 to the position shown in Fig. 5 the bars 30 will be securely locked in position and the remaining portion of the slack in the stencil 14 and the layer 16 will be taken by the ribs 24 forcing these parts into the grooves 25.

As shown in Fig. 9 the ribs 24' are adjustably mounted upon the bottom face of the top plate 17 to control the degree to which they will enter the grooves 25'. Screws 40 are rotatively but non-threadedly extended through the top plate 20 17 of the Mimeographer. The ribs 24' are formed of several sections securely attached together, with the bottom ends of the screws being threadedly engaged through the top sections of the ribs 24'. Enlarged heads 41 are formed on the 25 bottom end of the screws 40 and are disposed in complementary recesses 42 formed in the bottom sections of the ribs 24'.

Rotations of the screws 40 will cause the ribs 24' to move away from and towards the bottom 30 face of the top plate 17. It is impossible for the ribs 24' to become disengaged from the screws 40 because of the heads 41 on the screws which engaged the recesses 42.

The interior of the platen 10 is formed with 35 inwardly directed horizontal shelves 50 against which the bars 30 will clamp the ends of the stencil 14 and flannel layer 16 when the bars are secured in position by the clamping down of the top plate 17.

In other respects this form of the invention 40 is similar to the previous form and like reference numerals identify like parts in each of the several views.

In Fig. 12, the Mimeographer is illustrated in 45 use on a stack of cards or paper 60 placed in a tray 61, with a cutaway side 62 to expedite the removal of the uppermost card 60 after it is mimeographed by the device.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a postal card size Mimeographer having 60 a platen provided with a curved bottom face for the pad and stencil and a relatively flat top face the end portions of which are for supporting the ends of said stencil, a top plate extending across said platen and having end portions for engaging against the ends of said stencil, screw means for clamping said top plate down on said platen, and transverse ribs on the bottom faces of the end portions of said top plate and engaging complementary grooves in the end portions of the top face of said platen for gripping the end portions of said stencil, serrated bars for gripping the ends of said stencil and extended between said top plate and platen and having projecting ends, and means for holding said bars in several longitudinal positions on said platen while said top

plate is being clamped down by said screw means.

2. In a postal card size Mimeograph having a platen provided with a curved bottom face for the pad and stencil and a relatively flat top face the end portions of which are for supporting the ends of said stencil, a top plate extending across said platen and having end portions for engaging against the ends of said stencil, screw means for clamping said top plate down on said platen, and transverse ribs on the bottom faces of the end portions of said top plate and engaging complementary grooves in the end portions of the top face of said platen for gripping the end portions of said stencil, and means for holding said ribs in adjusted positions relative to the bottom face of said top plate for controlling the degree to which said ribs will enter said grooves.

3. In a postal card size Mimeograph having a platen provided with a curved bottom face for the pad and stencil and a relatively flat top face the end portions of which are for supporting the ends of said stencil, a top plate extending across said platen and having end portions for engaging against the ends of said stencil, screw means for clamping said top plate down on said platen, and transverse ribs on the bottom faces of the end portions of said top plate and engaging complementary grooves in the end portions of the top face of said platen for gripping the end portions of said stencil, serrated bars for gripping the ends of said stencil and extended between said top plate and platen and having projecting ends, and means for holding said bars in several longitudinal positions on said platen while said top plate is being clamped down by said screw means, comprising complementary serrations on the adjacent faces of the extended ends of said bars and the sides of said platen, and means on said top plate urging said bars into positions in which said serrations engage one another.

4. In a postal card size Mimeograph having a platen provided with a curved bottom face for the pad and stencil and a relatively flat top face the end portions of which are for supporting the ends of said stencil, a top plate extending across said platen and having end portions for engaging against the ends of said stencil, screw means for clamping said top plate down on said platen, and transverse ribs on the bottom faces of the end portions of said top plate and engaging complementary grooves in the end portions of the top face of said platen for gripping the end portions of said stencil, serrated bars for gripping the ends of said stencil and extended between said top plate and platen and having projecting ends, and means for holding said bars in several longitudinal positions on said platen while said

top plate is being clamped down by said screw means, comprising complementary serrations on the adjacent faces of the extended ends of said bars and the sides of said platen, and means on said top plate urging said bars into positions in which said serrations engage one another, comprising leaf springs mounted on the bottom face of said top plate and bearing against the ends of said bars urging them towards the serrations of said platen.

5. In a postal card size Mimeograph having a platen provided with a curved bottom face for the pad and stencil and a relatively flat top face the end portions of which are for supporting the ends of said stencil, a top plate extending across said platen and having end portions for engaging against the ends of said stencil, screw means for clamping said top plate down on said platen, and transverse ribs on the bottom faces of the end portions of said top plate and engaging complementary grooves in the end portions of the top face of said platen for gripping the end portions of said stencil, and means for holding said ribs in adjusted positions relative to the bottom face of said top plate for controlling the degree to which said ribs will enter said grooves, said ribs being formed of separate superimposed sections, and said means, comprising screws rotatively engaging said top sections and threadedly engaging said bottom sections to extend and retract said bottom sections when the screws are turned in one direction or the other.

6. In a postal card size Mimeograph having a platen provided with a curved bottom face for the pad and stencil and a relatively flat top face the end portions of which are for supporting the ends of said stencil, a top plate extending across said platen and having end portions for engaging against the ends of said stencil, screw means for clamping said top plate down on said platen, and transverse ribs on the bottom faces of the end portions of said top plate and engaging complementary grooves in the end portions of the top face of said platen for gripping the end portions of said stencil, and means for holding said ribs in adjusted positions relative to the bottom face of said top plate for controlling the degree to which said ribs will enter said grooves, said ribs being formed of separate superimposed sections, and said means, comprising screws rotatively engaging said top sections and threadedly engaging said bottom sections to extend and retract said bottom sections when the screws are turned in one direction or the other, said screws having their heads exposed from the top face of said top plate to be turned.

BENJAMIN GOLD.
